UNITED STATES PATENT OFFICE

JOHN SOHN, OF DEADWOOD, SOUTH DAKOTA

SANDAL

Application filed October 14, 1930. Serial No. 488,653.

This invention relates generally to sandals, and particularly to a sandal of highly decorative style and an excellent degree of comfort which is capable of being cheaply constructed, and which is made of one piece of material, and embodies a separate sole which is to be placed like an inner sole, the sandal comprising a plurality of fastening straps so related that the various advantages and features of novelty resident in the invention are accomplished in a manner which will be more fully understood as the description of the same is set forth in this specification.

It is an object of this invention to provide a sandal of the type described, which is attractive, light in weight, which may be quickly and easily and cheaply manufactured, and is admirably composed and arranged to conform to the idea of the invention.

These and other objects, the nature of the invention, its composition and arrangement and combination of parts will be readily understood by any one acquainted with the art to which this invention relates upon consulting the following descriptions of the drawings, in which:

Figure 1 is a general perspective view of my improved sandal.

Figure 2 is a vertical longitudinal section therethrough.

Figure 3 is a perspective view of the inner sole associated therewith.

Figure 4 is a plan view of the single blank from which the sandal is formed.

Referring in detail to the drawings, it will be seen that a sole portion generally indicated 5 has a gradually reduced forward portion 6 which merges into a strap 7 which is adapted to be brought back and over the foot as shown in Figure 1. At each side of the forward portion of the sole portion of the blank are provided oppositely longitudinally projecting straps 8 which

are adapted to be disposed as subsequently described. A similar pair of straps 9 having a wider base than the straps 8 lead from the side portion of the sole portion 5. Adjacent the heel portion 10 are a pair of laterally projecting short straps 11, and a pair of wings 12 are fashioned at the rear portion of the heel portion 10 and they are of somewhat curvate formation as seen in Figure 4, they form a covering for the side of the heel portion of the foot as hereinabove described. Just to the rear of the wings 12 are laterally projecting straps 13 which are adapted to be engaged about the ankle of the foot, as they are associated with a pair of parallel straps 14 which are also to be disposed about the ankle of the foot and above the straps 13, and said straps are connected by a web portion 15 which is adapted to engage the rear upper portion of the ankle.

Referring to Figures 1 and 2 it will be seen that the blank in Figure 4 below the heel portion 10 is perpendicularly erected, so that the wings 12 form walls rising from the sides of the heel portion 10 on each side thereof. Slits 16 are made in the said wings 12, and the straps 11 are projected perpendicularly, and through said slits and further perpendicularly extended to meet and to be bent about one of the straps 13, after passing through a slit 17 therein, and on one side of the sandal the strap 11 is permanently secured to the strap 13 by a fastener mounting a button 18 as shown in Figure 1. One of the straps 13 is made longer than the other and it is arranged as seen in Figure 1 to pass across the instep of the foot, and is provided with a buttonhole 19 for engaging upon the button 18. The straps 14 are secured about the ankle by a buttoning arrangement generally indicated 20 at one side of the ankle.

As seen particularly well in Figure 1 the portion 6 of the blank carrying the strap 7

is returned over the toes, and the strap 7 is extended backwardly over the foot and then upwardly where it is provided with a pair of slits 21 which permit it to be slipped upon the longer of the straps 14, after having passed through a slit in the front part of the straps 13. The straps 8 are then brought upwardly and inwardly over the strap 7, and then the straps 9 are brought upwardly and inwardly to cross the point of intersection of the straps 7 and 8, at which point of intersection they are secured together by a fastener carrying an external ornamental button as indicated at 22. An inner sole 23 is provided and placed upon the sole portion 5 of the blank and suitably secured thereto. It should be stated that the lower portion of the wings 12 are bent inwardly between the inner sole and the sole portion 5 and secured by means of stitching 26 which runs through the said sole portion 5. A slit 24 is provided for admitting the strap 11, the function and arrangement of which has already been described.

It is now thought to be obvious that I have provided a simple and inexpensive and highly attractive as well as comfortable sandal of new and novel type possessing advantages not heretofore known or practiced, and while I have set out herein specifically an example of my improved sandal, it is to be distinctly understood that I do not desire to limit the application of the invention to said particular example, but any change or changes may be made in material and structure and arrangement of parts consistent with the spirit and scope of the invention.

Having thus described the invention, what is claimed as new is:—

1. A sandal of the type described formed from a single blank of material, and provided with a separate inner sole, said blank comprising a sole portion, a heel engaging portion rising from the rear of the sole portion and provided with a plurality of ankle encircling straps, and portions thereof for engaging the sides of the heel; and a plurality of straps for engaging the toe portion of the foot and consisting of a central strap leading from the forward end of the sole portion and brought back over the foot to engage with the ankle encircling straps, and side straps for engaging the toe portion of the foot formed on the side edges of the forward portion of the sole portion, said straps brought to a common meeting point and there fastened together.

2. A one piece sandal having a separate inner sole, said blank comprising a sole portion, a heel engaging portion rising from the rear end of said sole portion and provided with a plurality of ankle encircling straps, and a toe engaging structure comprising a plurality of straps proceeding

from the peripheral edges of the toe portion of the sole portion and brought to a common meeting point over said sole portion to provide a pocket for reception of the toes of a foot, and one of said toe engaging straps being extended rearwardly to engage the said ankle encircling straps, and a separate inner sole disposed upon and fastened to said sole portion, and separable fasteners for said ankle encircling straps.

In testimony whereof I affix my signature.
JOHN SOHN.
